MASSACHUSETTS, ASSIGNEES, BY MESNE ASSIGNMENTS, TO KITSON MACHINE
SHOP, A CORPORATION OF MASSACHUSETTS.

HORIZONTAL OPENER AND CLEANER.

Application filed September 30, 1924. Serial No. 740,779.

The preliminary steps in the working of cotton into some finished form consist in opening the bales, removing the cotton therefrom, and acting on the compacted masses or wads of cotton to open them and remove the dirt therefrom. That is, the cotton as it comes from the bales is in a highly compressed condition and contains considerable quantities of sand, sticks, loam and other foreign materials which must be separated from it. Usually it is necessary to run the cotton through several machines designed to open the wads of cotton, loosen the fibre and work it into a fluffy condition while, at the same time, separating the dirt and foreign materials from the cotton fibre.

The present invention relates to machines of this general type and is especially concerned with the so-called horizontal type of cotton opener and cleaner.

A typical machine of this type includes a beater enclosed in a casing into which the cotton is usually conveyed by means of a current of air, a cylindrical screen encircling the beater, and a screw conveyer located under the screen and arranged to receive the dirt that falls through the screen and discharge it from the casing. In using machines of this type, it frequently happens that the dirt collects on the upper surface of the screen until a considerable quantity has accumulated, and then such an accumulation becomes loosened and falls into the conveyer in a mass too large for the conveyer to handle. This results in jamming the conveyer and necessitates the stopping of the machine and the clearing of the jammed parts.

It is one of the objects of this invention, therefore, to devise a cotton opening and cleaning machine which, while having the advantages of the present machines, will not be open to the objection just described.

The invention is also directed to the provision of a machine of the horizontal type which will be economical of power, will be reliable in operation, can be manufactured economically, and which generally will be an improvement upon the machines of this type heretofore devised. The invention involves both a machine of novel organization

and also novel details of construction, including particularly a unique arrangement for discharging the dirt from the casing while still maintaining the casing substantially air tight.

The nature of the invention will be readily understood from the following description when read in connection with the accompanying drawings, and the novel features will be particularly pointed out in the appended claims.

In the drawings, Figure 1 is an end view of a machine embodying the present invention;

Fig. 2 is a view, partly in vertical cross section and partly in side elevation, of the machine shown in Fig. 1; and

Fig. 3 is a diagrammatic view showing a common method of operating the machine.

The machine shown includes a beater comprising a horizontal drum 2 having a series of beater arms 3 projecting from its periphery. This drum preferably consists of a sheet metal shell secured on cast metal drum ends or heads, and these heads preferably have integral gudgeons or shafts 4 and 4' which are supported in ball bearings mounted in the frame of the machine. This arrangement permits the beater to rotate with very little friction. A pulley 5 is secured to the shaft or gudgeon 4 so that it may be belted to any convenient source of power. Encircling the beater 2 is a cylindrical screen which includes a perforated screen plate 6 secured to two annular drum ends or rings 7 and 8. The screen is rotatively supported at one end by three rolls 9, 10 and 11 (Fig. 1) which engage the periphery of the ring 8 while the ring 7 at the opposite end is similarly supported. This cylindrical screen may be rotated either in the same or the opposite direction to the rotation of the beater 2. As shown, it rotates in the same direction as the beater, but revolves very slowly. For the purpose of driving the screen, the ring 8 has gear teeth cut in its periphery to mesh with a driving pinion 12 mounted fast on the shaft 13 (Fig. 1). This shaft is rotated by a gear 14 secured thereto and driven by a pinion 15 on the shaft 16. The latter shaft carries a pulley

17 which is connected by a belt 18 to another pulley 20 secured on the end of the gudgeon 4.

Both the heater 2 and the screen 6 are enclosed in a sheet metal casing 21 which is provided with an inlet opening 22 at the left hand end (Figs. 1 and 2) and an outlet or discharge opening 23 at its opposite end. Preferably these openings project tangentially with reference to the path of rotation of the arms at the opposite ends of the beater.

When this apparatus is in operation, it is connected to a blower or some equivalent mechanism for creating a strong flow of air through the casing 21. A typical arrangement is shown diagrammatically in Fig. 3 in which the discharge outlet 23 is connected by a conduit with a condenser 24 which, in turn, is connected to the intake end of a blower 25. The blower thus creates a strong current of air through the cleaner casing 21 and the condenser 24 and this current of air carries the cotton into and through the cleaner. Immediately after the cotton enters the casing 21, it is struck by the beater arms, which are revolving rapidly, and it is carried in a more or less spiral path through the screen 6 and is finally ejected from the casing through the outlet 23. As it moves through the screen, each individual mass of cotton is struck many times by the beater arms, thus performing the double function of breaking up the wads of cotton and loosening the fibre and, at the same time, beating the dirt out of the cotton. Most of this dirt passes through the perforations in the screen 6 into the space between the screen and the casing 21. The dirt is prevented from accumulating in any substantial quantities on the screen, however, by the fact that the screen is rotated slowly. That is, any dirt which tends to pile up on the screen is dumped practically as fast as it gathers due to the rotation of the screen.

The dirt separated from the cotton must be discharged from the casing and a belt conveyer 28 is provided for this purpose. It should be observed that the air pressure within the casing is lower than that outside the casing because of the suction created by the blower 25, and it is necessary to effect this discharge of the dirt without permitting any substantial leakage of air through the casing. It will be seen from an inspection of Fig. 1 that the opposite walls of the casing at the lower side of the machine are inclined toward each other so that they direct the dirt on to the conveyer 28. The conveyer belt is supported on two pulleys 29 and 30, the latter pulley being secured to a shaft 31 which carries a worm wheel 32 meshing with a worm 33 secured on the driver shaft 16, above mentioned. The conveyer also includes a series of lugs 34 which

are secured transversely on the belt at regular intervals, each lug being faced with a strip of some yielding or resilient material such as rubber, leather, felt or the like. The casing of the machine comprises two semi-cylindrical sheet metal housings 37 and 38 respectively (Fig. 2), the former partially enclosing and being concentric with the pulley 29, while the latter is located in a similar relationship to the pulley 30. These housings are so spaced from the conveyer that the yielding faces 35 of the lugs 34 wipe against the inner surfaces of the housings, both at their ends and edges, as they travel around the pulleys 29 and 30, the ends of the facing strips 35 preferably being substantially flush with or projecting only very slightly beyond the opposite edges of the belt. The lugs are located so close to each other that at least two of them are always in contact with each of the casing members 37 and 38. This arrangement, therefore, effectually prevents the leakage of air past the ends of the conveyer, notwithstanding the fact that the conveyer is constantly in motion.

In order to further guard against leakage of air past the conveyer and into the casing, a plate 40 (Fig. 2) is located just under the upper reach of the conveyer belt and makes a tight joint at its opposite edges with the side plates of the casing, while it extends longitudinally of the conveyer substantially from the point at which the belt leaves the pulley 29 to the point at which it runs into engagement with the pulley 30.

It will now be evident that when the machine is in operation, the dirt removed from the cotton will fall continuously through the screen on to the conveyer and be discharged by it from the casing. The yielding faced lugs are valuable both for the purpose of preventing air leakage around the conveyer and also because they divide the conveyer, in effect, into pockets which hold the dirt and positively transfer it to a point outside the casing. This pocket arrangement also prevents any substantial disturbance of the dirt by currents of air while it is being discharged.

It will thus be evident that the present invention avoids any possibility of the machine being stopped by accumulations of dirt in the manner which has caused so much trouble in prior machines. The machine of this invention is, therefore, unusually reliable, and this is of importance not only from the standpoint of the production of an individual machine, but also because the shutting down of a cotton cleaner necessarily stops production of the entire series of machines which depend on it. While cotton has been above referred to as the fibre which the machine is particularly intended to handle, it is obvious that the

machine is adapted to handle other fibres, cotton being simply the most common example.

It will also be observed that the machine 5 is sturdy and substantial in construction, can be manufactured economically and is so organized that it requires a minimum of care and attention.

While we have herein shown and described 10 the best embodiment of our invention that we have so far devised, we do not desire to be limited to the exact details of the construction shown.

Having thus described our invention, what 15 we desire to claim as new is:

1. A cotton cleaning and opening machine comprising, in combination, a casing having inlet and outlet openings for the entrance and discharge of the cotton, mechanism 20 within said casing for acting on the cotton to separate the dirt therefrom, and a belt conveyer for receiving the dirt so separated and discharging it from the casing, said conveyer having yieldingly faced lugs spaced 25 thereon and extending transversely across the belt, and said casing having housings cooperating with said lugs to prevent any substantial leakage of air around the conveyer.

2. A cotton cleaning and opening machine 30 comprising, in combination, a casing having inlet and outlet openings for the entrance and discharge of the cotton, mechanism within said casing for acting on the cotton to separate the dirt therefrom, and a substantially horizontal belt conveyer travelling 35 through a compartment in the bottom of said casing and arranged to receive the dirt so separated and discharge it from the casing, said conveyer having yieldingly faced lugs spaced thereon and extending transversely 40 across the belt, and said casing having housings cooperating with said lugs to prevent any substantial leakage of air around the conveyer and including a horizontal plate 45 over which the upper reach of the belt travels and which connects the opposite side walls of the housing.

3. A cotton cleaning and opening machine 50 comprising, in combination, a substantially horizontal rotary beater, means for supporting said beater in its operative position, a rotary screen encircling said beater, means co-operating with the periphery of said screen to support it for rotation, mechanism 55 for rotating said screen, a casing enclosing said screen and beater, said casing having inlet and outlet openings at the opposite ends thereof, a horizontal belt conveyer located at the bottom of said casing and arranged to 60 receive the dirt which passes through the screen and to discharge it from the casing, said conveyer having yieldingly faced lugs spaced thereon and extending transversely across the belt, and said casing having hous-

ings cooperating with said lugs and belt to 65 prevent any substantial leakage of air around the conveyer and into said casing.

4. A cotton cleaning and opening machine comprising, in combination, a casing having inlet and outlet openings for the entrance 70 and discharge of the cotton, mechanism within said casing for acting on the cotton to separate the dirt therefrom, a substantially horizontal belt conveyer travelling through a compartment in the bottom of 75 said casing and arranged to receive the dirt so separated and discharge it from the casing, said conveyer having transverse lugs spaced therealong, pulleys supporting said belt and located closely adjacent to said casing, and housings connected with said casing and curved to fit around the portions of the conveyer travelling around said pulleys, said housings cooperating with the conveyer to prevent substantial leakage of air 80 around the conveyer.

5. A cotton cleaning and opening machine comprising, in combination, a rotary beater, a rotary screen encircling said beater, mechanism for driving said screen and beater, a casing enclosing said screen and beater, means for creating a current of air through 90 said casing to carry the cotton through the beater and casing, a continuously operating conveyor for discharging from the casing the dirt passed through said screen, inclined walls in said casing for directing the dirt into the conveyor, and means cooperating with said conveyor to prevent any substantial air leakage around the conveyor during 95 the discharge of the dirt.

6. A cotton cleaning and opening machine comprising, in combination, a substantially horizontal rotary beater, means for supporting said beater in its operative position, a rotary screen encircling said beater, means cooperating with the periphery of said screen to support it for rotation, mechanism for rotating said screen, a casing enclosing said screen and beater, said casing having inlet and outlet openings at the opposite ends thereof, means for creating a current of air through said casing to carry the cotton through the beater and casing, a horizontal belt conveyor located at the bottom of 100 said casing and arranged to receive dirt removed from the cotton and to discharge such dirt from the casing, said conveyor having transverse lugs spaced therealong, and housings cooperating with said lugs to prevent any substantial air leakage around the conveyor during the discharge of the dirt.

In testimony whereof we have signed our names to this specification.

JOHN K. WHITTIER.
FELIX D. LANGEVIN.
ROBERT S. CURLEY.

Certificate of Correction.

Patent No. 1,638,649.

Granted August 9, 1927, to

JOHN K. WHITPIER ET AL.

It is hereby certified that error appears in the printed specification of the above-numbered patent requiring correction as follows: Page 2, line 4, for the word "heater" read *beater*; and that the said Letters Patent should be read with this correction therein that the same may conform to the record of the case in the Patent Office.

Signed and sealed this 4th day of October, A. D. 1927.

[SEAL.]

M. J. MOORE,
Acting Commissioner of Patents.
